[57] CLAIM

The ornamental design for a weigh scale, as shown and described.

DESCRIPTION

FIG. 1 is a top and left front perspective view of a weigh scale showing my new design;

FIG. 2 is a top plan view thereof;

FIG. 3 is a front elevational view thereof;

FIG. 4 is a right side elevational view thereof, the left side being a mirror image thereto;

FIG. 5 is a rear elevational view thereof;

FIG. 6 is a bottom plan view thereof;

FIG. 7 is another embodiment of my new design of FIGS. 1-6 wherein the readout head has been suspended from the right side of the scale base;

FIG. 8 is a left side elevational view of FIG. 7;

FIG. 9 is a front elevational view of FIG. 7;

FIG. 10 is a bottom view thereof;

FIG. 11 is yet another embodiment of my new design of FIGS. 1-6 wherein the support arms are omitted and the readout head is shown in the wall mounted position;

FIG. 12 is a front elevational view of FIG. 11;

FIG. 13 is a right side elevational view of FIG. 11, the left side being a mirror image thereto;

FIG. 14 is a rear elevational view of FIG. 11; and

FIG. 15 is a bottom plan view thereof.

The broken-line showings of a wall surface are environmental only and form no part of the claimed design.
